UNITED STATES PATENT OFFICE

130,491

DESIGN FOR A TIRE

Ralph C. Lombard, Detroit, Mich., assignor to National Co-Operatives, Inc., Chicago, Ill., a corporation of Indiana

Application February 15, 1941, Serial No. 99,015

Term of patent 3½ years

To all whom it may concern:

Be it known that I, Ralph C. Lombard, a citizen of the United States, residing at Detroit, in the county of Wayne and State of Michigan, have invented a new, original, and ornamental Design for a Tire, of which the following is a specification, reference being had to the accompanying drawing, forming a part thereof, and in which

Fig. 1 is a development of the tread and side wall portions of a tire showing my new design;

Fig. 2 is a side view of a portion of the tire; and

Fig. 3 is a cross section taken substantially on line 3—3 of Fig. 2.

I claim:

The ornamental design for a tire, as shown.
RALPH C. LOMBARD.
